PROTECTIVE FIRE ALARM

Norbert Oliver Turner, Toronto, Ontario, Canada

Application June 23, 1950, Serial No. 169,867

6 Claims. (Cl. 116—106)

1

My invention relates to improvements in fire alarms of the mechanical type comprising an annunciator in the form of a bell and a striker motivated by an actuating mechanism including release means controlled by a fuse of metal having a low melting point.

The primary object of the invention is to provide an improved fire alarm of the character referred to comprising release means including an operating lever held in an operative position by means of a fusible strip of material. The fusible strip has a low melting point which renders it capable of readily melting in the presence of heat of an abnormal temperature such as that due to the presence of an outbreak of fire. The arrangement is such that should the fusible strip be melted by a condition of fire in the vicinity of the apparatus the operating lever frees the actuating mechanism in order to set the striker in operation for raising an alarm.

A further and important aim of the invention is to produce a reliable and serviceable fire alarm of the kind described which is inexpensive to manufacture and which is admirably suitable for use in dwellings and other places where an outbreak of fire is likely to occur. It is not intended that the invention shall be limited in its use since additional uses may be found for it and it may have as wide an application as fairly comes within the scope of the invention.

A still further and salient object of the invention is to provide a fire alarm structure in which the release lever carries a fixed detent and in which a spring motor actuates a striker and includes a gear or other rotatable element which is normally engaged by said detent to retain the spring motor against operation until an outbreak of fire occurs of an intensity such as to melt the fusible strip by which the operating lever is held in an inoperative position.

In one form of the invention the operating lever, when released by the fusible strip, is adapted to be vibrated by the engagement of the detent with teeth of a gear driven by the spring motor. A striker is carried by said lever in order to act on a bell for raising an alarm. The lever is resiliently pressed toward the gear as by a spring.

In a variant form of the invention there is an arrangement of resilient strikers carried by a gear or other rotary element and disposed to have wiping contact with depressing agents whereby they are caused to strike a bell when the gear is rotated.

With these and other objects in view the in-

2

vention consists in the novel construction and arrangement of parts as disclosed in the accompanying drawing and described in the ensuing specification.

5 In the drawing, Fig. 1 is a sectionized plan view of the invention taken substantially on the line 1—1 of Fig. 2.

Fig. 2 is a vertical sectional view of the invention.

10 Fig. 3 is a plan view similar to Fig. 1 but showing a variant form of the invention.

Fig. 4 is a fragmentary perspective view of the modified form of the invention showing how a striking element or hammer rides over a depressing agent for causing it to strike the bell.

15 Fig. 5 is a sectional detail taken on the line 5—5 of Fig. 1.

In carrying out my invention I provide a suitable support which is shown by way of example 20 as consisting of a base plate 6. Upon this base there is mounted a conventional form of spring motor comprising a main gear 7 journaled on a fixed spindle 8 and engaged with an idler gear 9 fixed on a spindle 10. The main gear 7 is made 25 rigid with a spring housing 11 containing a spiral spring 12. In the present instance the inner end of the spring 12 is fixed, as at 13, to the stationary spindle 8, and the outer end thereof is fixed to the housing 11, as at 14. The live spindle 10, which turns with the gear 9, may 30 be supported in any approved manner as by the bearing 15, and is supplied with a key 16 by which it can be turned.

With this arrangement it will be manifest that 35 the key 16 when turned in the proper direction will rotate the gears and thus wind the spring to store energy for an operative action in which the main gear reversely turns as a unit with the housing 11.

40 At a side of the main gear 7 there is provided a lever 17 pivoted at 18 and fashioned with an integral pawl or detent 19 of a tapered shape for engaging the interdental spaces of the main gear with an impositive action. According to this ar-

45 rangement the main gear can be turned by the key 16 in a direction to wind the spring. At the end of each turn of the key the main gear can be held against retrograde movement by applying hand pressure on the lever to cause the pawl or detent 19 to engage in a space between adjacent teeth to lock this gear against movement.

45 A fuse strip 20 of metal or comparable material is employed to retain the detent lever in its engaged position when the spring has been

wound. This strip is attached in a suitable manner, as for instance by the pins 21 and 22. The pin 21 upstands from the base 6 and is engaged in a hole 23 provided in one end of the strip. The pin 22 upstands from the distal end of the lever and is engaged in a hole 24 provided in the other end of the strip. In this way the lever is positively locked in its engaged position, but is capable of being freed by the melting of the fuse strip, as in the case of a fire. Spring pressure, such as that exerted by the leaf spring 25 is utilized to press the lever toward the main gear in order to cause the pawl or detent 19 to ride on the teeth of this gear when the lever is freed by the melting of the fuse strip. In this way the lever is induced to vibrate while the stored energy of the spring is being spent in turning the main gear. On the lever is a hammer 26 (Fig. 1) which is disposed to strike a bell 27 in each vibratory movement of the lever. The bell is an inverted cup-shaped member fastened on the fixed spindle 8.

Accordingly it will be manifest that the invention provides a serviceable and reliable fire alarm which can be placed in a room of a dwelling or otherwise located to sound an alarm in the event of a fire.

In the variant form of the invention illustrated in Figs. 3 and 4, the modification comprises the provision of one or more strikers on a rotary element of the spring motor in lieu of the hammer 26 previously described. Preferably said strikers are carried by the housing 11 which rotates concentrically within the bell 27. One or a plurality of these strikers may be employed and each comprises a rod 28 radially projecting from the side wall of the spring housing 11 and rigid therewith. Fixed on the outer end of said rod is a resilient arm 29 which extends backwardly in a circumferential manner with regard to the direction in which said housing turns in the unwinding of the spring 12. On the free end of the arm 29 is a spherical hammer-head 30 closely adjacent to but out of contact with the skirt portion of the bell. In the path of travel of the hammer-head 30 is a depressing agent 31 shown as a fixed upright having opposite angular sides 32 meeting at a crest 33. The heads 30 ride over the uprights 31 in the rotation of the spring housing 11 and therefore deliver a number of blows to the bell in each complete revolution of the main gear.

Upon the occasion of a fire in the immediate vicinity of the alarm device the melting of the fuse strip 29 releases the lever 17 which permits the main gear to be turned together with the housing 11 by means of the spring 12. During rotation of the housing the individual hammer-heads 30 approach the uprights 31 and are forced backwardly as they climb the adjacent inclined faces 32 thereof, whereupon they are freed abruptly as they ride over the crests 33. In this way they strike the bell with desirable force in order to raise an alarm. The oppositely arranged faces 32 enable the hammer-heads to pass thereover in reverse direction as is required when the spring 12 is being wound.

The invention provides a cheap and reliable fire alarm, and it will be understood that such changes and variations in constructional details may be resorted to as come within the scope of the appended claims.

What I claim is:

1. The combination in a fire alarm, of a support, a circular bell thereon, a rotator mounted on said support concentrically within said bell,

a hammer having a flexible arm extending outwardly and circumferentially from said rotator and having a head carried by said arm and disposed in close proximity to the skirt portion of said bell, and an upright element on said support and in the path of travel of said head, said upright element having inclined contact faces meeting at a crest over which said head is caused to ride in order to strike said bell.

5. 2. A protective fire alarm comprising a support, a bell thereon, a spring motor including a driven element rotatable about an axis concentrically of said bell, a resilient arm carried by said element and extending in a circumscribing manner about said element and within said bell, a strike head on the free end of said arm, and a depressing agent in the form of a fixed upright on said support and located interiorly of said bell, said upright having an angular face situated in the path of travel of said strike head whereby to depress the same to cause it to strike the bell when the strike head is moved past said angular face.

25. 3. A protective fire alarm comprising a support, a bell thereon, a spring motor including a driven element rotatable about an axis concentrically of said bell, resilient arms carried by said element in circumferentially spaced relation to extend in a circumscribing manner about said element and within said bell, strike heads on the distal ends of said arms, and a plurality of circumferentially spaced depressing agents in the form of uprights fixed on said support in close proximity to the skirt portion of said bell, said uprights having angular faces disposed to be engaged by said heads to effect a depressing action.

40. 4. In a fire alarm, a support, a bell thereon, a spring motor mounted on said support, said motor including a gear journaled concentrically of said bell, a striker device including a striker operated by said motor to hit said bell, a lever pivoted on said support, means on said lever providing a tapered dog for interdental engagement with said gear, and a strip of fusible material locking said lever to said support with said dog engaged with said gear to prevent sounding of an alarm in the wound condition of the motor until the fuse strip is melted as by outbreak of a fire.

5. 5. In a fire alarm, a support, a bell thereon, a spring motor mounted on said support, said motor including a gear and a spring housing both mounted concentrically of said bell at the open side thereof, resilient striker arms carried at the periphery of said housing and extending substantially circumferentially within the confines of said bell, heads on said striker arms, depressing agents in the form of uprights fixed 55 on said support in close proximity to the skirt portion of said bell, said uprights having angular faces disposed to be engaged by said heads during operation of said motor, a device retaining said motor inactive in the wound condition of said spring, said device including an element movably supported on said support and held in interdental engagement with said gear by a fusible strip.

6. 6. In a fire alarm, a support, a bell thereon, a spring motor mounted on said support, said motor including a gear and a spring housing both mounted concentrically of said bell at the open side thereof, resilient striker arms carried at the periphery of said housing and extending substantially circumferentially within the con-

fines of said bell, heads on said striker arms, depressing agents in the form of uprights fixed on said support in close proximity to the skirt portion of said bell, said uprights having angular faces disposed to be engaged by said heads during operation of said motor, a lever pivoted on said support and having a tapered dog, said dog having interdental engagement with said gear in an impositive manner, and a fusible strip forming a connection between said support and a distal part of said lever to retain the engagement of the lever.
